UNITED STATES PATENT OFFICE

PAUL K. CRAMBLETT, OF MILWAUKEE, WISCONSIN, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

MERCURY SWITCH METAL CLIP TYPE

Application filed November 24, 1938. Serial No. 321,587.

This invention relates in general to mercury switches and more particularly to mercury switches of the type which has a mercury to mercury make and break occurring on 5 the surface of the protective element of arc resistant material.

This type of mercury switch usually comprises an outer envelope which may be of soft glass or other suitable material. Within the 10 outer envelope is a protective element of arc resistant material which may be hard glass, porcelain, quartz, molded aluminum oxide or any other composition or substance capable of withstanding the high temperatures 15 and rapid temperature fluctuation as well as the other destructive forces set up by the arcing and tending to break down the structure of the switch. Usually such a protective element is in the form of a sleeve or cup. In 20 the present application, the protective element shown is embodied in various types of cup structures and each cup operates as a trap to confine a body of mercury. The mercury also has a shiftable portion which 25 makes and breaks contact with the mercury in the cup on the surface of the cup.

The problem of properly mounting a cup of this character within the outer envelope has given rise to a great deal of annoyance 30 and difficulty. The materials of the outer envelope and of the cup have different coefficients of expansion and the heating and cooling occurring in the use of the switch will result in breakage or fracture of the 35 elements of the switch if these parts directly contact with each other without sufficient clearance to allow for differential expansion and contraction.

One of the principal objects of the present 40 invention is to provide a novel and effective means of supporting or holding a protective element in proper position within the outer envelope while relieving the outer envelope of shocks and strains incident to arcing. 45 Along with these advantages the present in-

vention provides an extremely simple and comparatively inexpensive construction and is of such nature as to lend itself to efficient manufacturing process and to permit quick and easy assembly. Further, the construction is so sturdy and durable and so adapted to the requirements of the problem that it will stand up when in use over a long period. 50

Other objects and advantages reside in certain novel features of the construction, 55 arrangement and combination of parts which will be hereinafter more fully described and particularly pointed out in the appended claims, reference being had to the accompanying drawings forming a part of this 60 specification, and in which:

Figure 1 is a view in central vertical longitudinal section showing one embodiment of the invention and illustrating the switch as positioned when the portions of the mercury 65 are just about to make contact on a surface of the protective cup;

Figure 2 is a similar view illustrating the switch tilted just beyond the position indicated in Figure 1 with the portions of the 70 mercury in contact or united;

Figure 3 is a plan view of the internal structure of the switch shown in Figures 1 and 2 with the outer envelope shown in horizontal section;

Figure 4 is a view in central vertical longitudinal section showing a slightly different type of switch and illustrating the switch so positioned that the shiftable portion of the mercury is out of contact with the mercury 80 in both cups;

Figure 5 is a view similar to Figure 4 but illustrating the switch position so that the shiftable portion of the mercury makes contact with the portion of the mercury in one 85 cup;

Figure 6 is a view similar to Figure 5 but illustrating the reverse position of the switch;

Figure 7 is a plan view of the switch of 90

the type shown in Figures 3, 4 and 5, the envelope being shown in horizontal section and a slightly varied cup holder construction being illustrated;

- 5 Figures 8 and 9 are fragmentary detail views in top plan and in central vertical longitudinal section respectively, further illustrating the varied construction of the holders of the cups shown in Figure 7; and
10 Figure 10 is a view similar to Figure 9 showing the cup holder construction of Figures 1 to 7 inclusive.

Referring to the drawings and more particularly to Figures 1 to 3, inclusive, the numeral 1 designates an outer envelope which may be of soft glass or any other appropriate or suitable material. A protective element in the form of a cup 2 of hard glass, porcelain, quartz or other arc resistant material is positioned within the outer envelope and is located out of contact of the walls thereof. For supporting and holding the cup 2 in proper position and relation to the envelope 1 a spring clip 3 is provided and 25 consists of a split ring of stainless ferreous metal such as stainless steel or other suitable spring material. Opposite its split the ring 3 is formed with an outwardly and upwardly inclined holding arm 4 terminating in a socketed end 5 which receives the cup 2 and is cemented thereto as at 6. The spring clip 3 is resilient and it is tensioned slightly so that under the influence of its inherent resiliency it expands and frictionally grips the 30 inner wall of the envelope 1 when it is assembled therewith. A body of mercury is placed in the envelope 1 and has a portion 7a confined in the trap constituted by the cup 2 and also has a shiftable portion 7b disposed in the envelope outside of the cup and making and breaking contact with the portion 7a as the switch is operated. An electrode 8 is sealed in through the upper portion of the peripheral wall of the envelope 45 and extends down into the mercury 7a in the cup 2. Another electrode 9 is sealed in through one end of the wall of the envelope 1 and is immersed in the portion 7b of the envelope in all positions of the switch. 50 The cup 2 has a cylindrical portion 2a and a closed bottom 2b. The cylindrical portion 2a is cut away for a portion of its periphery at a point spaced from its upper end and from the bottom of the cup to provide an opening 10 through the peripheral wall of the cup and to form above this opening a shield 11 for the electrode 8, the shield being pressed inwardly toward the electrode whereby to better protect the same and to leave the clearance necessary for the unobstructed mercury movements necessary for making and breaking contact between the two portions of the mercury. As will be understood from Figures 1 and 2, the two portions 7a and 7b 65 of the mercury make and break contact over

the lip 2' constituted by the lower marginal wall of the opening 10 in the body of the cup. This marginal wall of the opening 10 is glazed or melted down or otherwise condensed and smoothed to provide a smooth polished surface which receives the arc inasmuch as it is on this surface that the two portions of mercury make and break. It has been found that glazing the surface which receives the arc enables the protective element to resist slotting under heavy currents. If the surface is left rough or merely ground, slotting under the influence of the arc rapidly progresses. The spring clip and holder thus described is not effected by the mercury or by the arc and yet it very effectively holds the protective element in proper position within the envelope 1 and out of contact therewith. It prevents the transmission of shocks and strains between the protective element and the outer envelope and thereby prevents breakage.

In the form of the invention shown at Figures 4, 5, and 6, the outer envelope of the switch is designated at 15 and may be of soft glass or other material. In this type of switch two protective elements or cups 16 and 17 are provided and as before are constituted of arc resisting material. The cups 16 and 17 are fitted and connected or secured as at 18a in sockets 18 and 19 formed on a double arm integral with a spring clip 22 which as in the previous embodiment comprises a split metal ring. In this embodiment of the invention, however, the ring or clip 22 is only of approximately circular form, the portion of the ring contiguous with the arm 20 being of the same flat formation as these arms. A body of mercury is placed in the envelope 15 and has portions 20a and 20b filling the cups 16 and 17 respectively, and also has a portion 20c which is shiftable in the envelope and alternately makes and breaks contact with the mercury 20a and 20b in the cups 16 and 17 respectively. Electrodes 23, 24 and 25 are sealed through the outer envelope 15 and are immersed in the portions 20a, 20b and 20c respectively of the mercury. The electrodes 23 and 24 project down through the upper open ends of the cups 16 and 17 into the mercury therein and are equipped with glass shields 27 which operate to prevent direct contact between the shiftable portion of the mercury and the electrodes. In this construction as in the previous embodiment of the invention the spring clip and holding means associated therewith operates to maintain the protective elements which receive the arc out of contact with the outer envelope and prevent the transmission of shocks and strains between the protective cups and the envelope. When this switch is rocked to the position shown in Figure 5, the shiftable portion 20c of the mercury makes contact with the portion 20a over the lip of 130

the cup 16 which may be glazed as in the previous embodiment of the invention. When the switch is rocked in an opposite direction, or to the position shown in Figure 5, 5 the shiftable portion 20c of the mercury makes contact with the portion 20b confined in the cup 17.

Obviously various means may be provided for suitably attaching or securing the cups 10 or protective elements to the spring clips or retaining elements. Thus, in lieu of cementing the cups to the sockets formed at the ends of the holding arm integral with the spring clips, each socket member may be split and 15 constituted to provide resilient retaining or gripping jaws as shown at 30 in Figures 7, 8 and 9, the jaws 30 snapping into a peripheral groove 31 provided in the associated protective cup.

20 In all embodiments of the invention the protective elements or cups are held in proper position within the outer envelope by means of a clip which is preferably constituted of spring metal and which cooperates with the 25 envelope and with the cups to maintain the cups in proper position. The protective elements and clips are completely made up outside of the envelope and may be easily assembled therein prior to the closing of the ends 30 of the envelope. In this connection it is to be understood that the envelope in its ordinary form is usually a tube with open ends. After the protective cups on the clips are assembled within the tube the ends of the tube are closed 35 and the electrodes sealed therein. As illustrated in the drawings each envelope has the usual tubulation through which the mercury is introduced, the air exhausted and the inner gas introduced. Finally the tubulation is 40 closed. As this is an established practice no further detailed explanation is necessary.

The invention claimed is:

1. A mercury switch comprising an outer envelope, a trap of arc-resistant material 45 therein, a body of mercury having a portion confined in said trap and a shiftable portion making and breaking contact with the portion in the trap, and means for holding the trap in position in the envelope including a resilient metallic ring like retaining element tensioned to frictionally engage the envelope and cooperable with the trap.

2. A mercury switch comprising an outer envelope, a protective element of arc resistant 55 material in said envelope, and a spring clip of stainless ferreous metal and of band-like structure for holding said protective element in position.

3. A mercury switch comprising an outer 60 envelope, a protective element of arc resistant material in said envelope, a body of mercury in said envelope having portions making and breaking contact on a surface of said protective element, and a split expansible retaining ring tensioned to frictionally engage the

inner wall of the envelope and in holding relation to said protective element.

4. A mercury switch comprising an outer envelope, a trap of arc resistant material therein, a body of mercury having a portion confined in the trap and a shiftable portion making and breaking contact with the portion in the trap, a spring clip within the envelope and engaged with the inner wall thereof, and a holder carried by the spring clip 70 and supporting said trap. 75

5. A mercury switch comprising an outer envelope, an element therein carrying a cup of arc resistant material, a spring clip coacting with said envelope and said element for holding the cup in proper position in the envelope, 80 said spring clip being flexible relative to the outer envelope although frictionally engaged therewith, and a body of mercury having a portion filling the cup and a shiftable portion making and breaking contact with the portion in the cup over a lip of the cup. 85

6. A mercury switch including an outer envelope, a protective cup of arc resistant material in said envelope, and a spring clip 90 engaged with the envelope and having an arm formed with a socketed portion receiving and secured to the cup.

7. A mercury switch comprising an outer envelope, a pair of cups of arc resistant material, an arm carrying said cups and disposing said cups in spaced relation within the envelope and a flexible spring clip cooperable with the envelope and with the arm for holding the cups in proper position of the envelope. 100

8. A mercury switch comprising an outer envelope, spaced traps of arc resistant material located within the outer envelope, an arm having socketed ends receiving and secured to said traps, a resilient retaining element coacting with an intermediate portion of the arm and with the envelope for holding the traps in proper position in the envelope, a body of mercury in the envelope having portions filling the traps and a shiftable portion making and breaking contact with the portions in the traps, electrodes sealed through the outer envelope and immersed in the portions of the mercury in the traps and an electrode sealed through the outer envelope and constantly immersed in the shiftable portion of the mercury. 110 115

9. A mercury switch comprising an outer envelope, a trap of arc resistant material 120 therein and a spring clip tensioned to expand and frictionally engage the outer envelope and having an integral arm terminating in a socket which receives and is secured to the trap. 125

10. A mercury switch comprising an outer envelope, a trap of arc resistant material therein, a resilient clip tensioned to expand and engage the inner wall of the outer envelope, and an arm integral with the clip and 130

having means for engaging and supporting the trap.

11. A mercury switch comprising an outer envelope, spaced traps of arc resistant material therein, a resilient clip engaged with the envelope and located between the traps, and a double arm integral with the clip, spaced from the outer envelope and having means to engage and support the traps.

10 In witness whereof, I have hereto affixed my signature.

PAUL K. CRAMBLETT.
